UNITED STATES PATENT OFFICE.

HARRY BARNETT MAPOU, OF NEW YORK, N. Y., ASSIGNOR OF ONE-HALF TO JACOB M. GREEN, OF NEW YORK, N. Y.

TIE.

Application filed April 24, 1926. Serial No. 104,487.

This invention relates to a tie.

An object of the invention is to provide a tie so constructed that no matter how much it is subjected to tension in the use thereof it will not wrinkle or lose its shape and if the material of the tie is temporarily pulled or stretched it will, when released, immediately resume its normal position.

A further object is to provide a tie so constructed as to achieve the above mentioned object without the use of any unusual material in the body of the tie or any unusual form of lining.

The invention is illustrated in the drawings, of which—

Figure 1 is a plan view of a tie laid out with the rear face upward;

Figure 2 is a similar view of part of a tie showing the body portion moved back to disclose the inner seam and the lining with the novel elastic member exposed;

Figure 3 is a section on the line 3—3 of Figure 1.

The form of the invention shown in the drawings is a preferred form, although it is understood that modifications in the construction and arrangement of the parts and in the character of the materials used may be adopted without departing from the spirit of the invention as set forth in the appended claims.

In effecting the production of a tie which was made of ordinary material with nothing unusually new about the body material or the lining, and yet one which when stretched in use will, when released, immediately resume its normal position and thereby resist indefinitely the tendency to wrinkle or tear, I have employed an elastic element which is connected along its length to the tie, but which is independent of the lining, if one is used. The point to which this element is connected I do not wish to limit to any particular location, but it is preferably on the inside of the tie along the seam formed between the meeting edges of the material. By attaching this elastic element to the tie preferably along the inner face of the seam I avoid the necessity of using any special form of lining or body material and get all required elasticity in the tie that is needed for everyday use. As the tie is pulled in use the

material will naturally stretch and in so doing will stretch the elastic element. Consequently, as soon as the tension is relieved from the material the elastic element will instantly restore it to its normal position and consequently the tie will not tend to form permanent wrinkles or become otherwise deformed.

The invention is extremely simple and efficient and requires no modification of any ordinary tie, but merely requires the sewing or attachment of an elastic element to the tie, preferably along the line mentioned above.

In the preferred form of the invention shown in the drawings, I show a tie having a body portion 10 of material, preferably made of silk, the free edges of which are connected together along the line 11 in the usual manner to form a seam. The tie may be provided with a lining 12 of any suitable material and cut in any desired manner. Preferably along the seam of the tie and preferably against the inner face thereof I fasten in any suitable manner an elastic element 13 which may be rubber elastic tape or other suitable material. This elastic element extends preferably substantially along the entire length of the seam and by being attached to the tie when the tie is in a normal unstretched condition will be extended when the tie is pulled so that as soon as the pull is released from the tie the elastic element will restore it to its normal position.

What I claim is:

1. In a necktie including a tubular body of a stretchable material and a lining, a rubber elastic tape independent of the lining secured to the inner ply of the body longitudinally thereof for tensioning the same against stretching and for returning the same to a normal unstretched position.

2. In a necktie including a tubular body of a stretchable material and a lining, an elastic element independent of the lining secured to the inside of the tubular body longitudinally thereof for tensioning the same against stretching and for returning the same to a normal unstretched position, said element consisting of a narrow length of rubber elastic tape.

HARRY BARNETT MAPOU.
